UNITED STATES PATENT OFFICE.

GEORGE H. FORSYTH, OF CHICAGO, ILLINOIS, ASSIGNOR TO MOTOR WHEEL CORPORATION, OF LANSING, MICHIGAN, A CORPORATION OF MICHIGAN.

DISK WHEEL.

Application filed May 4, 1922. Serial No. 558,495.

To all whom it may concern:

Be it known that I, GEORGE H. FORSYTH, a citizen of the United States, residing at Chicago, in the county of Cook and State 5 of Illinois, have invented certain new and useful Improvements in Disk Wheels, of which the following is a specification.

The present invention has to do with disk wheel construction and particularly with the 10 strengthening of the disk forming the wheel body against not only radial but also lateral stresses. The greatest stress to which an automobile wheel is subjected is not due to the dead weight of the car body and its load, 15 but rather to bad roads and unskillful driving. These may be grouped in one of two classes,—the radial blows received when the wheel strikes an obstruction in the line of travel or drops into a hole, and the lateral 20 stress resulting when the wheel strikes an object at an oblique angle and is driven or parked on a side hill.

The primary feature of the invention is the strengthening of the disk intermediate 25 the rim and its bearing upon the hub, by means of annularly spaced pockets, depressions or corrugations of substantial depth, and preferably by a secondary supporting disk which may or not carry such depressions, the secondary disk spaced from the 30 primary disk in the hub zone and bearing against the primary disk outwardly beyond the hub zone.

Two embodiments of the invention are set forth in the accompanying drawing by way 35 of exemplification, the figures of the drawing being taken from my application Serial No. 264,253, filed November 26, 1918, the said parent application having matured into Patent No. 1,373,184, dated March 29, 1921.

40 In the drawing,

Figs. 1 and 2 represent radial sections through disk wheels of slightly different construction but both embodying the invention.

45 Having particular reference to Fig. 1 of the drawing (corresponding to Fig. 8 of my parent application) the reference numeral 11 designates the main or primary disk of a wheel secured at its central portion be- 50 tween the hub plates 12 and 13, the latter of which is shown as developed into the front wheel of the brake drum 14. The connection between the disk and hub is effected by means of bolts 15 passing through holes

in the separator ring 16 which is disposed 55 between the two hub plates 12 and 13.

Adjacent its peripheral portion the said disk is provided with a shoulder 17, outwardly beyond which the disk bears to the rear, forming the felly portion 18 marginally inclined at 19 to form a rear stop for the demountable rim 20. A front rim-retaining member 21 which may be in the form of a plurality of individual clips or a single annular clip is seated at its lower edge upon 60 the shoulder 17 and with its upper edge bears against and supports the front edge of the rim 20.

A secondary disk 22 is similarly secured to the hub and in the hub zone is spaced 70 from the primary disk 11 and extends in its main portion radially to the periphery where its margin is housed within the lipped over portion 23 of the primary disk. At 75 annularly spaced intervals, outwardly beyond the hub zone, the secondary disk is provided with depressions 24 having their bottoms aligned in parallel relation to the primary disk at 25, bearing against the same in lateral supporting relation. In this bearing area the two disks may be secured together by the clip securing bolts 26 or they may be spot welded. Outwardly beyond the contact area 25 the outer wall of the pocket depression extends laterally beneath and in 80 radial supporting contact with the felly portion 18 of the primary disk 11, as indicated at 27.

As shown in Fig. 2 of the drawing (corresponding to Fig. 13 of the parent application) the primary disk 30, shouldered at 31 to support the rim-retaining member 21, extends rearwardly beyond said shoulder to substantially the median plane of the wheel, and thence forwardly at 32 beneath the rim 20.

The secondary disk 33 is spaced from the primary disk 30 adjacent the hub, whereas outwardly beyond the hub zone and in the area indicated at 34 the two disks are disposed in lateral supporting contact, being aligned in parallel relation, where they may or not be rigidly joined as by spot welding. Between the hub and rim the secondary disk 33 is provided with annularly distributed pocket-like depressions 35 abrupt at the one end 36 and at the other end 37 merging gradually into the general plane of the disk. 100 In both forms of construction shown the

secondary disk, being spaced from the main disk at the hub and in contact therewith outwardly beyond the hub zone, constitutes an efficient lateral support for the primary disk and are fixedly connected therewith or otherwise clipped against radial shifting, also supports the disk against radial stresses.

It will be observed that in both of the forms of construction shown the depressions or corrugations are pocket-like, of substantial depth, and comparatively short, differing in this respect from attenuated corrugations made to simulate spokes and as sometimes resorted to for stiffening. The precise location of the depressions and their exact conformation will depend upon the particular cross-sectional contour of the wheel and any auxiliary reinforcements employed. They may be disposed nearer the hub than the rim, or mid-way, or adjacent the periphery as here shown, depending upon the disk contour and the presence or

absence of hub supporting members such as the hub plate or brake drum.

I claim:

1. In a wheel of the class described, a main supporting front disk and a secondary reinforcing rear disk, the two disks aligned together in the region immediately outside of the hub zone, and the secondary or reinforcing disk having stiffening relatively short corrugations disposed annularly at intervals between the hub and rim.

2. In a disk wheel, a hub having radial flanges, a main front disk, and a reinforcing rear disk, the two disks in lateral supporting contact outwardly beyond the hub zone while spaced apart adjacent the hub and confined between the hub flanges, the rear disk provided adjacent its periphery with annularly spaced relatively short stiffening corrugations.

In testimony whereof I have hereunto subscribed my name.

GEORGE H. FORSYTH.
